UNITED STATES PATENT OFFICE.

WILLIAM PATON FRASER, OF EDINBURGH, SCOTLAND.

HAT-FASTENER.

SPECIFICATION forming part of Letters Patent No. 715,048, dated December 2, 1902.

Application filed December 26, 1901. Serial No. 87,299. (No model.)

To all whom it may concern:

Be it known that I, WILLIAM PATON FRASER, a subject of the King of Great Britain, residing at Edinburgh, county of Mid-Lothian, 5 Scotland, have invented certain new and useful Improvements in Hat-Securing Devices, of which the following is a full and complete specification, such as will enable those skilled in the art to which it appertains to make and 10 use the same.

This invention relates to devices for securing a lady's hat on her head; and the object thereof is to provide an improved device of this class which is simple in construction 15 and operation and which in practice is secured in the crown of a hat and may be operated for the purpose desired whenever necessary.

In the drawings forming part of this specification, in which the separate parts of my improvement are designated by the same reference characters in each of the views, Figure 20 1 is an inside view of a hat or hat-form provided with my improvement; Fig. 2, a cross-section thereof, and Fig. 3 a plan view of a 25 detail of the construction.

In the practice of my invention as shown in the drawings I provide a yoke-shaped spring *a*, the sides of which are provided with 30 inwardly-directed spiral coils *a*², having outwardly-directed members *a*³, which project at an angle to the transverse cross-head portion *a*⁵ of the spring, and in practice I preferably employ two of these devices and secure there- 35 on segmental clamps *b*, provided with comb-teeth *b*², the ends of the clamps *b* being folded around the spiral coils *a*², as shown at *b*³, and when the clamps *b* are thus connected with the coils *a*² of the spring *a* the projecting 40 members *a*³ of the coils *a*² extend between the folded portion *b*³ of said clamps and the body thereof, as shown at *b*⁴. In practice these devices, including the spring *a* and the clamps *b*, are secured in the crown of the hat 45 in any desired manner; but, as shown in the drawings, I employ for this purpose a stiff transverse strip *c*, to which said devices are secured by a thread or cord *d* passing through the spring-coils *a*², as shown in Fig. 2, and 50 through the folded portions of the clamps *b* and around the strip *c*, and said strip is secured in the crown of the hat in any desired manner. I also connect a cord *e* with each of

the clamps *b* and pass said cord out through the side of the crown of the hat and provide 55 the same with a handle or end piece *f*, and by means of these cords the clamps *b* may be drawn outwardly, as shown in dotted lines in Fig. 2, and also farther than is shown in dotted lines in Fig. 2 or until the teeth *b*² rest 60 against the side of the crown, and in this position of said clamps the hat is placed on the head, the cords *e* are released, and the clamps are thrown inwardly and the teeth *b*² enter 65 the hair and securely hold the hat on the head. It will be understood that the cross-head portions *a*⁵ of the springs *a* operate to throw the clamps *b* inwardly, and in the form of construction shown in the drawings the parts *a*⁵ bear on the end portions of the strip 70 *c*; but said strip *c* is not absolutely necessary, and the clamps may be secured, as will be readily understood, to the crown of the hat, in which construction the parts *a*⁵ of the spring *a* would bear on the crown of the 75 hat. It will also be apparent that one of these devices may be employed instead of two; but I prefer to employ two, as better results are secured thereby.

Having thus fully described my invention, 80 what I claim as new, and desire to secure by Letters Patent, is—

The herein-described devices for securing a hat to the head comprising a transverse plate adapted to be secured in the top of the crown 85 of the hat and spring-operated clamps connected with said plate and arranged longitudinally thereof, the adjacent ends thereof being curved segmentally and provided with teeth and the other end being formed into a 90 roll through which are passed spring members, said spring members being provided with outwardly-directed extensions adapted to bear on said plate, and said clamps being provided with flexible devices adapted to be 95 passed outwardly through the side of the crown of the hat, substantially as shown and described.

In testimony that I claim the foregoing as my invention I have signed my name, in presence of the subscribing witnesses, this 10th day of December, 1901.

WILLIAM PATON FRASER. [L. S.]
